UNITED STATES PATENT OFFICE.

MARTIN LUTHER RUSSELL, OF RENFREW, ONTARIO, CANADA, ASSIGNOR OF
TWO-THIRDS TO WILLIAM ALBAUGH, OF OVID, AND CHARLES A. KEELER,
OF ROCHESTER, NEW YORK.

BELT-TIGHTENER.

SPECIFICATION forming part of Letters Patent No. 294,678, dated March 4, 1884.

Application filed December 20, 1883. (No model.)

To all whom it may concern:

Be it known that I, MARTIN LUTHER RUSSELL, a subject of the Queen of Great Britain, and a resident of Renfrew, in the county 5 of Renfrew and Province of Ontario, Canada, have invented certain new and useful Improvements in Devices for Tightening Cables and Machine-Belts; and I do hereby declare that the following is a full, clear, and exact 10 description of the invention, which will enable others skilled in the art to which it appertains to make and use the same, reference being had to the accompanying drawings, which form a part of this specification, and in 15 which—

Figure 1 is a plan view of my improved device for tightening cables and machine-belts. Fig. 2 is a vertical sectional view on line $x-x$, Fig. 1. Fig. 3 is a similar view on line $y-y$, Fig. 1, and Fig. 4 is a vertical sectional view on line $z-z$ in the same figure.

Similar letters of reference indicate corresponding parts in all the figures.

My invention has relation to devices for 25 tightening cables and machine-belts; and it consists in the improved construction and combination of parts of the same, as will be hereinafter more fully described and claimed.

In the accompanying drawings, A represents the pulley-wheel, through which motion is conveyed from the source of power; and B B represent the journal-boxes in which the ends of the shaft upon which the said pulley-wheel is supported revolve. These journal-boxes are adjustably secured upon blocks C C, being provided on their lower sides with guide-blocks D D, which slide within grooves E E, extending longitudinally upon the upper side of the blocks C C, and also with downwardly-projecting pieces F F, provided with screw-threaded apertures F' F', for the purpose hereinafter specified.

G G represent screws, which work in suitable bearings upon the blocks C C, each screw being journaled longitudinally and centrally upon that face or side of the blocks C C upon which are the longitudinal grooves E E, and passing through the screw-threaded apertures F' F' in the downwardly-projecting pieces F F,

previously referred to. By turning these 50 screws the journal-boxes B B, and thereby the pulley-wheel A, can be drawn to any desired distance from the source of power, thereby keeping the drive-belt tight and in running order.

Upon one end of the pulley-wheel shaft A' is secured a bevel-pinion, H, adapted to mesh with a similar bevel-pinion, I, secured upon a shaft, J. This shaft J works in journal-boxes K K, and has upon one of its extremities a pinion, L, adapted to communicate power to any point through any suitable system of shafts and pinions, and is provided with a longitudinal groove or recess, M, for the purpose hereinafter set forth. The pinion I, with which the bevel-pinion H meshes, is adjustably secured upon that part of the shaft J lying between the journal-boxes K K by having a key, N, passing through a collar, I', upon one side of the said pinion, adapted 55 to fit with its lower end within the longitudinal groove M. By this arrangement the bevel-pinion I can be moved horizontally upon the shaft J, so as to continue to mesh with the pinion H on the end of the pulley-wheel shaft A' 60 when the said pulley-wheel is moved for the purpose of tightening the drive-belt, as before stated.

From the foregoing description, taken in connection with the accompanying drawings, 65 the construction and operation of my improved device for tightening cables and machine-belts will readily be understood without requiring further explanation.

It will be seen that my improved device is 70 simple in construction, and, being devoid of all complicated mechanism, is not liable to get out of order. By its use cables and machine-belts can readily be kept tight and in operative position.

Having thus described my invention, I claim 75 and desire to secure by Letters Patent of the United States—

In a device for tightening cables and machine-belts of substantially the described construction, the combination of the pulley-wheel shaft A', having pulley-wheel A and bevel-pinion H, adjustable journal-boxes B B, hav-

ing guide-blocks D D and downwardly-projecting piece F, provided with a screw-threaded aperture, F', blocks C C, having longitudinal grooves E E, adjusting-screws G G, with 5 the shaft J, having a longitudinal groove or recess, M, and bevel-pinion I, having a key, N, to adapt it to be adjustably secured upon the grooved shaft J, all constructed and arranged to operate substantially in the manner and for 10 the purpose shown and set forth.

In testimony that I claim the foregoing as my own I have hereunto affixed my signature, in presence of two witnesses, this 28th day of November, A. D. 1883.

MARTIN LUTHER RUSSELL.

Witnesses:

CALVIN RUSSELL,
JAMES SIMPSON.
